(57) **CLAIM**

The ornamental design for a valve housing, as shown and described.

DESCRIPTION

FIG. 1 is a right, front, top perspective view of a valve housing showing my new design;

FIG. 2 is a left, front, bottom perspective view thereof;

FIG. 3 is a front elevational view thereof;

FIG. 4 is a right elevational view thereof;

FIG. 5 is a rear elevational view thereof;

FIG. 6 is a left elevational view thereof;

FIG. 7 is a top plan view thereof;

FIG. 8 is a bottom plan view thereof;

FIG. 9 is a right elevational view thereof; and,

FIG. 10 is a right, front, top perspective view thereof.

The dotted lines shown in the figures are included for the purpose of illustrating environment and form no part of the claimed design.
